United States Patent Office.

W. G. HAMILTON, OF MILTON, WISCONSIN.

Letters Patent No. 99,313, dated February 1, 1870.

IMPROVEMENT IN WATER-ELEVATORS.

The Schedule referred to in these Letters Patent and making part of the same

To all whom it may concern:

Be it known that I, W. G. HAMILTON, of Milton, in the county of Rock, and State of Wisconsin, have invented a new and useful Improvement in Water-Elevators; and I do hereby declare that the following is a full, clear, and exact description thereof, which will enable others skilled in the art to make and use the same, reference being had to the accompanying drawing; forming part of this specification.

This invention relates to improvements in water-elevating apparatus, whereby it is designed to simplify and improve the apparatus patented to me, March 2, 1869, No. 87,408; and

It consists in an arrangement of the tilting-spout, which receives the water from the buckets, so that it will be restored after the buckets pass by it, by gravitation, thereby dispensing with all restoring-apparatus.

Figure 1 represents a sectional elevation, and

Figure 2 represents a plan view of my improved apparatus.

Similar letters of reference indicate corresponding parts.

A and B represent the buckets, having curved lugs C attached to their sides, to which chains D are connected, and which work over grooved pulleys E on a crank-shaft, carrying the said buckets down on one side with the open ends downward, so as to fill and turn right end up at the bottom, and be carried up on the other side to discharge into the tilting-spout F. Thus

far the arrangement is similar to that of the previous patent above alluded to.

The present invention consists in so pivoting, or otherwise arranging the spout F, that it will be heaviest at the discharging-end, and in providing the stop G to prevent it from being tilted, so far as to carry the heavy end H beyond the centre on the upper side.

By this arrangement, the spout which is tilted downward at the end toward the buckets, by the buckets when they pass down after emptying, will be instantly restored by gravitation to the position for discharging the water of the next bucket, as soon as the emptied bucket has passed from contact with the said spout.

This arrangement dispenses with all necessity for tilting-apparatus, and materially simplifies and cheapens the apparatus.

Having thus described my invention,

What I claim as new, and desire to secure by Letters Patent, is—

The combination, with the buckets A B, arranged for emptying as described, of a tilting-spout, arranged to be restored to the discharging-position after the buckets have passed, by gravitation, and provided with a stop, G, all substantially as specified.

W. G. HAMILTON.
